CLAIM

The ornamental design for an automotive vehicle, as shown and described.

DESCRIPTION

FIG. 1 is a perspective view showing the front and left side of an automotive vehicle of my new design;

FIG. 2 is a perspective view showing the rear and left side thereof;

FIG. 3 is a top plan view thereof the opposite side being substantially a mirror image of that shown; and

FIG. 4 is a side elevational view thereof.

Fig. 1.Fig. 2.
